UNITED STATES PATENT OFFICE.

WILLIAM C. RENTZ, OF ATLANTA, GEORGIA.

SPARK-PLUG.

1,337,959.

Specification of Letters Patent. Patented Apr. 20, 1920.

Application filed July 21, 1919. Serial No. 312,250.

To all whom it may concern:

Be it known that I, WILLIAM C. RENTZ, a citizen of the United States, residing at Atlanta, in the county of Fulton and State 5 of Georgia, have invented new and useful Improvements in Spark-Plugs, of which the following is a specification.

This invention relates to an improved form of spark plug, and has for its primary 10 object the provision of a plug capable of three functions; namely, a spark producer, an intensifier, and a primer.

Another object of the invention is the 15 novel manner of constructing and associating the various elements so as to accomplish the foregoing functions at a minimum expense.

Besides the above my invention is distinguished in the novel manner of associating 20 an intensifying device with the plug so that an intensifying spark gap can be produced at will.

With these and other objects in view the 25 invention will be better understood from the following detailed description taken in connection with the accompanying drawing, wherein:

Figure 1 is a side elevation of the device. Fig. 2 is a vertical section view. 30 Fig. 3 is a top plan view. Fig. 4 is a section view on line 4—4. Fig. 5 is a section view of the intensifying electrode. Fig. 6 is a top plan view thereof.

Fig. 7 is a plan view of the switch arm. Fig. 8 is a section view of a slight modified 35 form of my invention.

Figs. 9—10—11—12 are side elevation of other forms of my invention.

Again referring to the drawing illustrating one form in which my invention may be 40 constructed the numeral 1 designates the bushing within which is rigidly clamped by a cap 2 a core of insulation 3. Suitably 45 placed gaskets 4 are provided to accomplish an air-tight connection between the parts just described. Formed within and extending lengthwise of the bushing 3 is a passage 5, the outlet 6 of which is disposed to one 50 side of a main electrode 7, and an auxiliary electrode 8 of the spark plug. A pet-cock 9 closes the passage 6, but when open allows gasoline to pass through the passage to the engine cylinder for priming the same. The 55 intensifying attachment for the plug consists of a sleeve 11 clamped between the cap

2 and a second cap 12. This sleeve 11 is provided with eight openings 13 through which a view may be had of a sight tube 14 which incloses an end portion of the electrode 7 and an end portion of an intensifying electrode 15 now to be described. This electrode 15 is threaded in a cap 10 so as to vary the distance of the intensifying spark gap 16. Slidably mounted within the electrode 15 is a contact 17 arranged to be pressed by a spring 18 to a position to bridge the gap 16 and thereby cut out of circuit the intensifying spark gap. The contact 17 has connected thereto a stem 19 so constructed 70 that a portion thereof may be placed in either of a pair of slots 20 and 21, of different depths so that the contact may be either spaced from the electrode 7 or allowed to move into engagement therewith. 75

To complete the invention I provide a switch 22 which controls the passage of current from the binding post 23 to the electrode 15. The binding post 23 is carried by a switch arm 24 which has an adjustable 80 connection with the cap 10.

In Fig. 8 I have shown a check valve 25 substituted for the pet-cock 9 so that it may be automatic in its operation.

In the form of my invention shown in 85 Fig. 9, I have dispensed with switch 22 and have connected directly to the stem of the intensifier, finger piece 26 of insulating material, so that by grasping this finger piece the intensifying contact may be adjusted for 90 the production of an intensifying spark gap or for the omission of the same. The spark plug illustrated in Fig. 10 is identical with that illustrating Fig. 1, with the exception that the switch arm 24 and a portion of the 95 switch 22 are bent at an angle as illustrated at 27, so that the plug may be readily used in confined spaces, such as occur in airplane engines. In Fig. 11 I have shown a switch in the form of a coil spring 28 one end of 100 which is clamped to the binding post 29 while the remaining end is adapted to be hooked around or disengaged from the intensifying electrode by pulling on the insulation finger grip 29. 105

If found advantageous in practice, the spring pressed intensifying contact 17 can be dispensed with and a manually adjustable thumb screw 30 substituted which is threaded to the plug in a position to close the intensifying spark gap 31 when the screw is adjusted the required amount. 110

It is of course to be understood that the invention may be constructed in various other manners and the parts associated in other relations, and therefore I do not desire 5 to be limited in any manner except as set forth in the claims hereunto appended.

What I claim is:—

1. In an accessory for internal combustion engines, the combination of a spark plug including 10 an electrode made up of an inner section, an outer tubular section constituting a switch member and the inner end of which is spaced from the inner section and the outer end of which is exposed and provided 15 with open slots at angles to each other and of different depths, and an endwise movable contact rod sheathed in the tubular section and having an enlargement at its inner end backed by a spring inclosed in the tubular 20 section and also having a finger portion at its outer end capable of being placed in

either of the slots of the tubular section, and a complementary switch member carried by the plug and movable into and out of direct engagement with the outer exposed end of 25 said tubular member of the electrode.

2. A spark plug for internal combustion engines, comprising an electrode made up of an inner fixed section, an outer tubular fixed section the inner end of which is open and spaced from the inner section and the outer end of which is exposed and provided with open slots at angles to each other and of different depths, and an endwise movable contact rod sheathed in the tubular section 30 and having an enlargement at its inner end backed by a spring inclosed in the tubular section and also having a finger portion at its outer end capable of being placed in either of the slots of the tubular section. 35

In testimony whereof I affix my signature. 40

WILLIAM C. RENTZ.
